LATCH FOR DOORS, DRAWERS, WINDOWS OR THE LIKE

Morris De Lee, 2645 Yates Ave,
Los Angeles, Calif. 90022

Filed May 24, 1968, Ser. No. 12,079

Term of patent 14 years

Int. Cl. D8—03

U.S. Cl. D8—109

FIG. 1.

FIG. 2.

FIG. 3.

FIG. 4.

FIG. 5.

FIG. 1 is a front elevational view of a latch for doors, drawers, windows or the like showing my new design;

FIG. 2 is a side elevation thereof;

FIG. 3 is a rear elevation thereof;

FIG. 4 is an end elevational view of the latch as viewed from the left side of FIG. 2; and

FIG. 5 is an end elevational view thereof as seen from the right side of FIG. 2.

The dominant features of my design reside in the portions shown in full lines.

I claim:

The ornamental design for a latch for doors, drawers, windows or the like, as shown and described.
